UNITED STATES PATENT OFFICE.

EDOUARD LAPOINTE, OF NEW HAVEN, CONNECTICUT.

FOLDING LUNCH-BOX.

No. 884,824.

Specification of Letters Patent.

Patented April 14, 1908.

Application filed May 27, 1907. Serial No. 376,010.

To all whom it may concern:

Be it known that I, EDOUARD LAPOINTE, a citizen of the United States, residing at New Haven, in the county of New Haven and State of Connecticut, have invented a new and useful Improvement in Folding Lunch-Boxes; and I do hereby declare the following, when taken in connection with the accompanying drawings and the letters of reference marked thereon, to be a full, clear, and exact description of the same, and which said drawings constitute part of this specification, and represent, in—

Figure 1 a perspective view of a lunch-box constructed in accordance with my invention, and shown as broken down and with the cover applied to it. Fig. 2 a corresponding view with the cover removed. Fig. 3 a perspective view of the box set up but with the cover off. Fig. 4 a view of the box in front elevation as set up and with the cover on. Fig. 5 a broken perspective view showing one of the corners of the box to illustrate the initial positions of its setting up fins and ears when the box is being set up. Fig. 6 a broken plan view of one of the front corners of the box, showing the position of the parts before the front of the box is sprung to "jump" its setting-up ear from the inside to the outside of the adjacent end-piece. Fig. 7 is a like view showing the ear as so "jumped."

My invention relates to an improvement in folding lunch boxes, the object being to produce at a low cost for manufacture, a simple and durable box constructed with particular reference to carrying a napkin when folded, and to convenience in being speedily "set up" and "knocked down."

With these ends in view, my invention consists in a folding lunch box having certain details of construction as will be hereinafter described and pointed out in the claims.

In carrying out my invention as herein shown, I employ a shallow tray 2 having end-flanges 3, 4, and front and rear flanges 5, 6, all of these flanges being of the same height and producing a tray of sufficient depth to not only receive the front-piece 7 and back-piece 8, and the end-pieces 9 and 10 of the box, but also to receive a napkin, knife, fork and spoon, or anything else which may be desired to keep in the box when it is knocked down. The said front-piece 7 is hinged to the flange 5, the back 8 to the flange 6, the end-piece 9 to the flange 4, and the end-piece 10 to the flange 3, the said parts being

constructed in the usual manner for being hinged together.

For the purpose of locking the front 7, back 8 and end-pieces 9 and 10 together, the said end-pieces are formed upon their side edges with setting-up fins 11, 11, extending to their lower edges but terminating below their upper edges, while the upper edges of the front and back-pieces 7 and 8 are formed with corresponding setting-up ears 12, 12, arranged so as to clear the upper ends of the fins 11. The fins 11 stand at a right angle to the end-pieces 9 and 10 and are located in planes parallel with the planes of the front 70 and back-pieces 7 and 8 when the box is set up. On the other hand the ears 12 stand at a right angle to the front and back-pieces 7 and 8 and are located in planes parallel with the end-pieces 9 and 10. When the box is 75 set up the said fins 11 and ears 12 are thus arranged at right angles to each other.

To set up the box, the end-pieces 9 and 10 and the front and back-pieces 7 and 8 are elevated so that when the said parts are 80 brought into their vertical or final positions, the fins 11 will be on the outside of the box, and the ears 12 on the inside of the box as shown by Fig. 5. The metal from which the parts are made being thin and flexible, the 85 upper ends of the front and back-pieces are now sprung outward so as to permit the ears 12 to be "jumped", so to speak, from the inside to the outside of the box as illustrated by Figs. 6 and 7. The four corners of the 90 box having been treated in this way, a very rigid structure is obtained in less time than it takes to tell it.

To "break down" the box, the upper ends of the front and back-pieces 7 and 8 are 95 sprung outward enough to disengage the ears 12 from the upper corners of the end-pieces 9 and 10 after which the front and back-pieces 7 and 8 may be folded inward, and then the end pieces 9 and 10. When the latter are folded inward as shown in Fig. 2, the fins 11 shut over the front and rear flanges 5 and 6 of the tray 2. The flanged cover 13 fits over the upper edges of the front and back 7 and 8 and the end-pieces 9 and 10 100 when the box is "set up", as shown in Fig. 4, and over the tray 2 when the box is "knocked down" as shown in Fig. 1. In each of these situations the cover excludes any dust from 105 the box.

For convenience in removing the cover from the box when "set up", and when

"broken down", its side flanges are by preference formed with thumb-notches 14. To secure the cover in place when the box is "set up", I employ two straps 15, 15, riveted 5 to the end-pieces 9 and 10 and furnished with a buckle 16 of any approved form. When the box is "knocked down" the straps are folded up out of the way within the tray.

I claim:—

- 10 In a folding lunch box, the combination with a shallow tray having a front flange, a back flange and two end flanges, of a front-piece, a back-piece and two end-pieces respectively hinged to the said front and back 15 and end flanges of the said tray which is adapted in depth to receive the said front and back pieces when the box is "broken down"; and a cover adapted to fit the box when "set up", and to fit the tray when the box is 20 "broken down", the said end-pieces being provided on their side edges with setting-up

fins standing at a right angle to them, and located in planes parallel with the said front and back pieces when the box is "set up", and the said front and back pieces being provided 25 at their upper corners with setting-up ears standing at a right angle to them and located in planes parallel with the planes of the said end-pieces when the box is "set up", and the said fins and ears being located at right angles to each other, and the said ears being sprung from the inner to the outer faces of the said end-pieces in "setting-up" the box, and from the outer to the inner faces of the said end-pieces in "breaking down" the box. 30

In testimony whereof, I have signed this specification in the presence of two subscribing witnesses.

EDOUARD LAPOINTE.
